UNITED STATES PATENT OFFICE.

FELIX LAWERNCE SAINO, OF MEMPHIS, TENNESSEE.

FIREPROOF STRUCTURE.

SPECIFICATION forming part of Letters Patent No. 794,316, dated July 11, 1905.

Application filed January 23, 1905. Serial No. 242,318.

To all whom it may concern:

Be it known that I, FELIX LAWERNCE SAINO, a citizen of the United States, residing at Memphis, in the county of Shelby and State of Tennessee, have invented certain new and useful Improvements in Fireproof Structures; and I do declare the following to be a full, clear, and exact description of the invention, such as will enable others skilled in the art to which it app-
10 pertains to make and use the same.

My invention relates to improvements in fireproof structures for doors, window-shutters, and the like.

The object of my invention is to provide a simple and comparatively inexpensive fire-
15 proof structure of this character which will not warp when subjected to intense heat.

With the above and other objects in view the invention consists of certain novel fea-
20 tures of construction, combination, and ar-
rangement of parts, as will be more fully de-
scribed, and particularly pointed out in the
appended claims.

In the accompanying drawings, Figure 1 is
25 a side elevation of a fireproof structure in the
form of a door constructed in accordance with
my invention. Fig. 2 is an edge view of the
same. Fig. 3 is an elevation of one end of
the door. Fig. 4 is a vertical longitudinal
30 sectional view taken on the line 4-4 in Fig. 3.
Fig. 5 is a vertical transverse sectional view
taken on the line 5-5 in Fig. 1, and Fig. 6 is
a horizontal sectional view taken on the line
6-6 in Fig. 1.

35 In the drawings I have illustrated a fire-
proof door 1 made of a fireproof structure
which is constructed in accordance with my
invention. The structure is composed of a
plurality of sections 2 of substantially rec-
40 tangular form, arranged side by side in con-
tact with each other with their edges out-
turned. The sections 2 are similar in con-
struction and each consists of a body or core
3, preferably of wood and in the form of a
45 board or block, an inner covering 4, of asbestos
or other non-combustible material, and an
outer covering 5, of metal, preferably sheet
metal. The inner covering 4 is preferably in
the form of a sheet of asbestos paper wrapped
50 around the side faces and edges of the board

or body 3, and the metallic outer covering 5
is preferably formed in two parts or sections
6 6, each of which is of three-sided form and
is engaged with one edge of the body or board
3. Referring to Fig. 6, it will be seen that of 55
the sections 6 each envelops one edge of the
board and terminates in a line coincident with
the rod 14, as indicated in dotted line in Fig.
5. The side portions 7 of the metal covering-
sections 6 terminate at the ends of the board or 60
body 3, and the central portions 8 of said sec-
tions are formed at their ends with projecting
portions 9. These portions 9 are engaged
with side flanges 10, which are formed upon
metal connecting plates or strips 11, which 65
are arranged upon the ends of the sections 2.
As clearly shown in Fig. 5 of the drawings,
the portions 9 are bent over the flanges 10, as
at 12, and the latter, together with said por-
tions 10, are then bent inwardly upon the 70
outer face of the plate or strip 11. It will
be seen that this construction unites the sec-
tions 2 into a solid body; but in order to unite
them more securely the ends 13 of the plates
or strips 11 are bent inwardly upon the sec- 75
tions 2 at the ends of the door. I preferably
further unite the sections 2 by bolts or tie-
rods 14, which extend through the section, as
clearly shown in Figs. 4 and 6 of the draw-
ings. The sections 2 at the ends of the door 80
have their outer faces covered, preferably, by
a metal plate or strip 15, which has its side
edges interlocked, as shown at 16, with the
side edges of the metallic coverings 5 upon
said sections, as clearly shown in Fig. 5 of 85
the drawings.

It will be seen that a door, window-shutter,
or other object constructed as described will
not warp or be otherwise affected by the most
intense heat. This is due to the arrangement 90
of the sections side by side with their edges
outturned and to their covering of asbestos
and metal, as will be readily understood.

While I have shown and described the pre-
ferred embodiment of my invention, it will 95
be understood I do not wish to be limited to
the precise construction herein set forth, since
various changes in the form, proportion, and
the minor details of construction may be re-
sorted to without departing from the princi- 100

ple or sacrificing any of the advantages of this invention.

Having thus described my invention, what I claim as new, and desire to secure by Letters 5 Patent, is—

1. A fireproof structure composed of a plurality of united sections placed side by side with their edges outturned, each of said sections consisting of a strip of wood provided 10 with an inner covering of asbestos or the like and an outer covering of metal, substantially as described.

2. A fireproof structure for doors and the like, comprising a plurality of sections, each 15 consisting of an inner strip or body, an inner covering of asbestos or the like, and an outer covering of metal, said sections being arranged side by side with their edges outturned, and bolts or tie-rods extending through said sections for the purpose of uniting them, substantially as described.

3. A fireproof structure for doors and the like, comprising a plurality of sections, each 25 consisting of an inner strip or body, an inner covering of asbestos or the like and an outer covering of metal having projecting portions at its ends, said sections being arranged side by side with their edges outturned, flanged metallic locking - plates arranged along the 30 ends of said sections and having their side flanges interlocked with the projecting portions of said metallic coverings and tie-rods

or bolts extending through said sections, substantially as described.

4. A fireproof structure comprising a plurality of sections arranged side by side, and each consisting of a body and a metal covering therefor having projecting portions at its ends, and connecting end plates having side flanges engaged with projecting portions of 40 said metal coverings and bent inwardly to secure said sections together, substantially as described.

5. A fireproof door or the like comprising a series of sections arranged side by side, and 45 each consisting of a strip of wood, an inner covering of asbestos or the like and an outer covering of metal formed with projecting end portions, flanged plates or strips arranged along the ends of said sections and having 50 their ends bent over upon the end sections and their flanges bent inwardly in engagement with the projecting portions of said metal coverings, and bolts or tie-rods passed through said sections, substantially as de- 55 scribed.

In testimony whereof I have hereunto set my hand in presence of two subscribing witnesses.

FELIX LAWERNCE SAINO.
